FIG 1

FIG 2

Inventor

Hugh G. Moran

By *Wilfred E. Larson*

ATTORNEY

UNITED STATES PATENT OFFICE

2,566,903

DENTAL APPLIANCE

Hugh G. Moran, St. Louis, Mo.

Application August 27, 1948, Serial No. 46,475

2 Claims. (Cl. 33—174)

1

This invention relates to a dental appliance and the primary object of the invention is to provide a device of this kind to facilitate the making of dentures in a manner to restore substantially the normal aspect of the face.

It is also an object of this invention to provide means whereby the proper vertical level of the mandible may be determined in edentulous mouths and in a manner whereby artificial dentures may be made to function more efficiently and preserve the harmonious vertical contour of the face.

With the condyles of the mandible seated in their fossae, the jaws are in normal functional vertical relation when the inclined plane of the body of the mandible is parallel with the inclined plane of the maxilla from the head of the condyle to the ala of the nose. It is an object of the invention to provide a device to determine those planes in an edentulous mouth for transfer to a mechanical articulator.

The vertical relation of the mandible to the maxilla is based upon the premise that the skeletal frame of human face originates at like centers, and develops along definite lines, forming a biological pattern, to facilitate the coordination and function of the mandible and its associated structures; that this pattern is applicable to all human faces, notwithstanding the differences in their size, form, length or breadth, (with the exception of major deformities); that it is not changed by the growth, development, or atrophy of the skeletal frame of the face, but from a physiological standpoint remains constant through life; that the proportion of the upper two-thirds of this pattern is maintained by the integral bones of the skeletal frame of the cranium and face, while from a functional viewpoint the proportion of the lower one-third is supported in large measure by the normal dentition. Consequently, this lower proportion may be altered by the loss, abrasion or other abnormalities of the natural dentition, resulting in a diminution of that proportion, which shortens the vertical dimension of the face, and adversely affects its normal harmonious contour, gives rise to a malposition of the condyles in the temporo-mandibular fossae, upsets the muscular balance of the dental mechanism, changes the angle at which the mandible normally approaches the maxilla, and reverses the direction of force normally exerted by the mandible against the maxilla, all of which impair the maintenance of health, function, comfort and facial expression. It is a further object of the invention to provide a device to determine such relationship in the completion of a trial plate.

2

The invention consists in the details of construction and in the combination and arrangement of the several parts of my improved dental appliance whereby certain advantages are attained, as will be hereinafter more fully set forth.

In order that my invention may be better understood, I will now proceed to describe the same with reference to the accompanying drawings, wherein:

10 Figure 1 is a view of a device embodying the invention and diagrammatically shown applied to the face, with different positions of the mandible.

Figure 2 is an enlarged detail sectional view taken substantially on the line 2—2 of Figure 1.

15 Figure 3 is an enlarged detail sectional view taken substantially on the line 3—3 of Figure 1.

As illustrated in the accompanying drawings, 1 denotes a plate possessing a certain amount of flexibility but normally maintaining a predetermined longitudinal curvature. In the present embodiment of the invention, this plate 1 is of a shape substantially to conform to the contour of the face. The apex portion of the plate 1 is provided with an opening 2 which is adapted to be placed upon the head of a condyle of a mandible. The opposite end portion of the plate 1 is shown as stepped, the outermost portion 3 determining the bottom of the device when in use.

Disposed lengthwise of the plate 1, are the slots 30 4 and 5 diverging from the opening 2 in the apex portion of the plate 1. The slots are on a relative angle of approximately thirty (30°) degrees. Substantially midway of the slots 4 and 5 is a third slot 6 also disposed lengthwise of the plate 1.

35 Overlying the top slot 4 is the inner portion of an elongated flexible arm 7. This arm 7 is snugly but freely disposed through a slot 8 closely adjacent to the forward end of the plate 1. The rear portion of the arm 7 is disposed over the outer face of the plate 1 and carried by said rear portion of the arm 7 is a headed member 9, the shank a of which being freely disposed through the slot 4 with the head b underlying the plate 1 and of a diameter greater than the width of the slot 4.

40 45 Threading upon the free end portion of the shank a is a holding nut 10 which coacts with the outer face of the arm 7. By required adjustment of the nut 10, the frictional resistance to the movement of the arm 7 may be regulated to assure the maintenance of the arms 7 in a selected endwise adjustment.

50 55 The outer extremity of the arm 7, is reduced in width to provide a pointed end 11, said reduced portion 12 being of such length to permit the desired endwise adjustment of the arm 7, to bring the pointed end 11 to the ala of the nose when the

opening 2, in the apex or rear portion of the plate 1 is over the head of a condyle. It is to be particularly pointed out that the pointed end 11 is in a plane radial to the opening 2.

Overlying the outer face of the plate 1 and the forward portion of the slot 5, is a second elongated flexible arm 14 having its inner or rear portion provided with an element 15 disposed through the slot and frictionally holding the arm 14 to the plate 1, said element 15 being similar to the friction holding means hereinbefore described in association with the arm 7.

The outer portion 16 of the arm 14 is also transversely reduced to provide a pointed end 17 adapted to register with the point of the chin when the opening 2 of the plate 1 is on the head of the condyle of the mandible. This pointed end is also on a plane radial to the opening 2 and the pointed end 11 of the arm 7 and the pointed end of the arm 14 are spaced thirty (30°) degrees on a circle of which the opening 2 is the axis.

The arm 14 is snugly but freely disposed through a guide slot 18 suitably provided at the forward portion of the plate 1.

Overlying the outer face of the plate 1, and the forward portion of the slot 6 is a third elongated flexible arm 19 also snugly but freely disposed through a slot 20 in the forward portion of the plate 1. The arm 19 carries a tensioning means 21 similar to that of the arms 7 and 14 for selectively holding the arm 19 in endwise adjustment.

The outer end portion 21 is also transversely reduced in width to provide a pointed end 22 in a plane radial to the opening 2 of the plate. The pointed end 22 is adapted to be brought into register with the occlusion line of the maxillary teeth at the vertical line of the face as determined by the plane between the ala of the nose and the point of the chin.

In the use of the device, the same is applied to the right side of the face of the patient after the trial plate with the bite runs attached have been placed on the edentulous ridges. The device is pressed as closely as possible against the skeletal frame of the face with the opening 2 overlying the head of the condyle of the mandible. The inherent flexibility of the plate 1 will permit the same to closely conform to the contour of the face. The arm 7 is then adjusted endwise until the pointed end 11 is accurately positioned at the ala of the nose and at the vertical center of the face.

After the selected adjustment of the arm 7, the intermediate arm 19 is adjusted, endwise to bring the pointed end 22 thereof to the vertical center of the face. By this adjustment the pointed end 22 will indicate the occlusional plane of the anterior teeth. The bite rim of the upper trial plate will then be built up or reduced as may be necessary to bring the plane of said bite rim into the plane determined by the pointed end 22 of the arm 19.

After the plane of the bite rim of the upper trial plate has been determined, the arm 14 is endwise adjusted to bring the pointed end 17 thereof to the vertical center line of the face. If the height of the bite rim of the lower trial plate is correct, the pointed end 17 will register with the point of the chin, as shown at x in Figure 1 of the drawings, when the mandible is closed. In the event the bite should be too high, when the mandible is closed, the pointed end 17 will be above the center point of the chin, as at y, in Figure 1, and should such rim be too low, the pointed end 17 will be below the point of the chin. The dentist can either decrease or increase the

height of the bite rim until the pointed end 17 registers with the point of the chin which indicates the correct level of the mandible.

The correctness of the device as herein disclosed is due to the fact that the length of the human face, at the vertical center from the hair line to the point of the chin, when the mandible is in normal vertical functional position is ninety (90°) degrees with respect to the heads of the condyles of the mandible. The length from the ala of the nose to the center of the chin is one third of such major center line or thirty (30°) degrees with respect to the heads of the condyles of the mandible. The normal occlusal plane of the anterior teeth is fifteen (15°) degrees below the ala of the nose with respect to the heads of the condyles. Obviously the pointed end 22 of the arm 19 is spaced 15° with respect to the pointed end 11 of the arm 7.

Disposed through the opening 2, of the plate 1, is a tubular member 23 which constitutes a pivotal mounting for an end portion of a relatively short straight arm 24. Secured as at 25, to this arm 24, for longitudinal adjustment lengthwise thereof, is a second straight arm 26. This outer extremity of this arm 26 is continued by an elongated straight arm 27 disposed outwardly on an angle of one hundred twenty (120°) degrees with respect to the arm 26. These arms 24, 26 and 27 possess a certain degree of flexibility.

To assure the correctness of the arms 7, 14 and 19 while the plate 1 is still in position on the face with the opening 2 of the plate 1 over the head of the condyle of the mandible, the arm 26 is lengthwise adjusted along the arm 26, to bring the heel point 28 at the juncture of the arms 26 and 27 to the point of the angle of the mandible. If the arms 7, 14 and 19 have been set or adjusted, the arm 27 will be parallel with the top arm 7.

The approved trial plates while in the oral cavity are locked together for transfer to the mechanical articulator.

It is to be particularly pointed out that the opening 2 of the plate 1 constitutes an index to assure the proper placement of the plate 1 upon the face of the patient.

From the foregoing description it is thought to be obvious that a dental appliance constructed in accordance with my invention is particularly well adapted for use by reason of the convenience and facility with which it may be assembled and operated.

I claim:

1. In a dental appliance of the character described, a flexible plate having a reduced end portion provided with an aperture and a flared outer end portion having its end edge formed to provide spaced, angularly disposed, stepped portions, flexible arms mounted endwise on said plate and extending outwardly of said stepped portions in substantial alignment with the said aperture, an eyelet mounted in the said aperture, a relatively short arm having one end engaged with said eyelet for pivotal movements relative to said plate and depending therefrom, and an angled flexible arm having a relatively short end portion connected endwise with said short arm and a longer end portion extending forwardly below said plate and the lowermost of the first arms, said plate being adapted to be placed against a side of the face with the said eyelet centered over a condyle of the mandible and the outer ends of the first arms terminating in the vertical center of the face, with the said end of the upper-

most arm at the ala of the nose, the like end of the intermediate arm in the occlusal plane of the teeth, and the like end of the lower arm at the center of the chin, the free end of the longer portion of the angled arm at the approximate point of the chin.

2. The appliance as defined in claim 1, with means for adjusting the first arms endwise on said plate, one independently of the other, and other means for adjusting the short end portion 10 of the said angled arm endwise on said short arm, whereby the outer ends of all of said arms may be accurately aligned in the plane of the vertical center of the face.
